UNITED STATES PATENT OFFICE

94,190

DESIGN FOR AN APRON

Bettie Davis, Chicago, Ill.

Application July 18, 1933, Serial No. 48,750

Term of patent 3½ years

To all whom it may concern:

Be it known that I, Bettie Davis, a citizen of the United States, residing at Chicago, in the county of Cook and State of Illinois, have invented a new, original, and ornamental Design for an Apron, of which the following is a specification, reference being had to the accompanying drawing, forming part thereof.

The figure is a plan view of an apron, showing my new design, the same showing the contour of the apron with the apron strings broken away.

I claim:

The ornamental design for an apron, as shown and described.

BETTIE DAVIS.
